DESIGN FOR A FLUORESCENT LIGHTING FIXTURE

George John Creed, Milton, Mass.

Application June 8, 1944, Serial No. 113,910

Term of patent 14 years

(Cl. D48—23)

To all whom it may concern:

Be it known that I, George John Creed, citizen of the United States, residing at Milton, in the county of Norfolk and State of Massachusetts, have invented a new, original, and ornamental Design for a Fluorescent Lighting Fixture, of which the following is a specification, reference being had to the accompanying drawing, forming part thereof.

Figure 1 is a perspective view of a fluorescent lighting fixture showing my new design;

Figure 2 is a partial elevation of the fixture shown in Figure 1; and

Figure 2 is a partial bottom view of the same.

I claim:

The ornamental design for a fluorescent lighting fixture, as shown.

GEORGE JOHN CREED.
